UNITED STATES PATENT OFFICE.

WILLIAM S. FERRIS, OF ELKHART, INDIANA.

BACK REST FOR CHAIRS.

Application filed April 18, 1928. Serial No. 270,822.

This invention relates to improvements in back rests for chairs and it consists of the matters hereinafter described and more particularly pointed out in the appended claims.

5 The primary object of the invention is to provide an improved back rest for use in connection with a single supporting post and which permits of a ready adjustment of the back rest for the comfort and convenience 10 of the occupant of the chair.

A further object of the invention is to provide a construction of this kind which may be made substantially all of metal at a relatively low cost and which will hold the back 15 rest in the desired adjusted position and against turning on the post but will permit the tipping of the back rest member with respect to its associated parts so that said member will readily fit and conform to the back 20 of the occupant.

These objects of the invention as well as others, together with the many advantages thereof will more fully appear as I proceed with my specification.

25 In the drawing:

Fig. 1 is a view in side elevation of a chair provided with my improved back rest construction.

Fig. 2 is a plan view of my improved back 30 rest construction on an enlarged scale.

Fig. 3 is a vertical sectional view through the improved back rest construction and top end of its associated supporting post as taken on the line 3—3 of Fig. 2.

35 The invention is herein illustrated and will be herein described as embodied in that type of chair now known as a "stenographer's chair" but this is to be considered as by way of illustration only, because as will be apparent, the improved back rest construction may also be embodied in other types of chairs where its peculiar characteristics makes it of advantage to do so.

Referring now in detail to that embodiment 45 of the invention illustrated in the accompanying drawing, 1 indicates as a whole the base of the chair, 2 indicates the seat frame and seat thereof which is mounted on the top end of a seat post 3 having a swivelling bearing with respect to said base. 4 indicates the back rest post which in this instance is made of metallic tubing and is operatively connected at its bottom end to the rear side of the seat frame at its middle for a limited fore 50 and aft rocking movement. From the seat

frame, said back rest post curves upwardly and then forwardly to terminate in a vertically disposed top end part 5 which is closed by a plug 6 as best shown in Fig. 3. In said top end post 5 of the post at the rear side 60 thereof is provided a plurality of longitudinally spaced openings 7—7.

Associated with the top end part 5 of the back rest post, is a back rest which includes a horizontally disposed, transversely and 65 rearwardly curved back rest member 8 to the rear face of which is secured a flat bar 9, the ends 10—10 of which are bent to form rearwardly extending ears. 11 indicates a second flat bar which though spaced rearwardly from the bar 9 substantially conforms in curvature therewith and has its ends 12—12 bent to form forwardly extending ears which are pivoted to the ears 10—10 of said bar 9 as by rivets 13—13, so that the 75 back rest is supported by said bar 11.

The mid portion of the supporting bar is formed to provide a rearwardly opening seat 14 with which coacts a rearwardly extending yoke or bridge 15 that has ears 16—16 fixed 80 to the bar 11 at each side of the seat 14. In said yoke is fixed in any suitable manner, a filler block 17 which coacts with the seat to provide a recess that receives the top end of the post 5 with a fairly snug fit. Threaded 85 through the rear portion of the yoke and its associated filler block 16 is a screw 18 and the inner end of said screw is tapered to enter any one of the openings 7 in the post while the other end has a hand wheel 19 by which the 90 screw may be threaded or turned in either direction.

When the back rest has been adjusted to the proper height on the post end, the screw is turned to enter the desired opening 7 in the 95 post whereby the back rest is held in its adjusted position and against twisting or turning on the post. When the back rest has thus been adjusted and a person occupies the 100 chair, the back rest 8 will pivot on the rivets 13 to conform with the back of the occupant.

The yoke and filler block construction gives the proper length of screw threaded bearing for the screw by which the beveled end thereof may be securely forced into that opening 7 in the post end 5 in line therewith so that said screw cannot accidentally loosen up to that extent which will permit the back rest to drop downwardly on the post.

The construction described, comprises but 110

a few parts which are readily made and assembled which is efficient in operation for its intended purpose.

While in describing my invention, I have referred in detail to the form and arrangement of the various parts thereof, I do not wish to be limited thereto except as may be pointed out in the appended claims.

I claim as my invention:—

- 10 1. In combination with a back rest post, a back rest member, a supporting member therefor, a yoke carried thereby and coacting with a part of said supporting member to surround said post, a block carried by the yoke and a screw, threaded through said block to engage the post to lock said supporting member thereto.
- 15 2. In combination with a back rest post, a back rest member, a supporting member

therefor having a depressed portion therein to receive said post, a yoke fixed to said supporting member and bridging said depressed portion, a block fixed in said yoke and a screw threaded into said block to engage said post to lock the supporting member thereto.

25 3. In combination with a back rest post having a plurality of longitudinally spaced openings therein, a back rest member, a supporting member therefor having a depressed portion therein to receive said post, a yoke fixed to said supporting member and bridging said depressed portion, a block fixed in said yoke and a screw threaded in said block to engage in the desired opening to lock the supporting member to said post.

30 35 In testimony whereof, I have hereunto set my hand, this 15th day of March, 1928.

WILLIAM S. FERRIS.
